UNITED STATES PATENT OFFICE.

CHARLES G. LUNDSTROM, OF CHICAGO, ILLINOIS.

DEVICE FOR FINDING THE AXES OR CENTERS OF CIRCULAR BODIES, OPENINGS, OR PLANE FIGURES.

1,081,682.

Specification of Letters Patent. Patented Dec. 16, 1913.

Application filed May 10, 1913. Serial No. 766,689.

To all whom it may concern:

Be it known that I, CHARLES G. LUNDSTROM, a citizen of the United States, and a resident of the city of Chicago, county of Cook, and State of Illinois, have invented certain new and useful Improvements in Devices for Finding the Axes or Centers of Circular Bodies, Openings, or Plane Figures, of which the following is a specification.

- 10 My invention relates to improvements in means for readily and easily finding the axis or center of a solid opening or plane figure of oval, elliptical or circular form.
- 15 The object of my invention is the production of a device of the character mentioned which will be of simple and economical construction and through the medium of which the axis or center of a solid, opening or 20 plane figure of the form mentioned may be located with the greatest ease and expedition.

Other objects will appear hereinafter.

The invention consists in the combinations and arrangements of parts hereinafter described and claimed.

The invention will be best understood by reference to the accompanying drawing forming a part of this specification, and in 30 which—

Figure 1 is a top plan view of a device embodying my invention, the same being shown arranged for finding the axes of a circular body or plate and also the axes 35 of a circular opening, said solid member and said opening being shown in dotted lines, Fig. 2 is a view similar to Fig. 1 showing the device arranged for use in the location of the axes of an elliptical plane figure, Fig. 40 3 is an enlarged perspective view showing one of the angular members which register with the periphery of the plane figure, as shown in Fig. 2, and Fig. 4 is an enlarged section taken on line $\alpha^4-\alpha^4$ of Fig. 1.

45 The preferred form of construction as illustrated in the drawing comprises two substantially T-shaped members which are entirely separate and independent of each other. Each of said members comprises an 50 elongated thin flat stem 1 and a transversely extending cross piece 2 which is rigidly secured to said stem, screws being preferably used in this connection. The cross pieces 2 are provided with spaced perforations 55 adapted for engagement by pins 4.

In using the device for finding the axes or center of a solid member or plate, or of an opening, the stems 1 of the parts of the device are arranged with longitudinal edges contiguous as clearly shown in Fig. 1. The 60 pins 4 are then adjusted in the perforations 3 to the positions desired, said perforations being spaced at equal distances as shown from the contiguous edges of the stems 1, the pins 4 being always engaged with the 65 corresponding perforations, that is, said four pins 4 will be engaged with the four perforations 3 which are equally distant from said contiguous edges of said stem. The pins 4 are of a length sufficient to extend 70 through the cross pieces 2 and project below the same as clearly shown in Fig. 4 and so that, in the use of the device to find the center or axes of a solid member or plate or of an opening, said pins will engage 75 against the periphery of said member or said opening. The two parts of the device are moved relatively to each other with the adjacent edges of the stems 1 in constant contact until all four of the pins 4 contact 80 with the periphery of the solid member 5 or of the opening 6 in the member 7, as the case may be, as clearly shown in Fig. 1. When all of said pins so contact the axis of the solid figure or opening acted upon will 85 be coincident with the contiguous edges of the stems 1, and so that by removing one of the parts of the device, as shown in dotted lines in Fig. 1, the exposed longitudinal edge of the stem 1 of the other may be used as a 90 straight edge in describing the axis. It will be understood of course that where it is desired to find the center, it is only required to repeat the adjustments described in order to locate a second axis, it being clear that 95 the center will be at the point of interception of the two axes thereof.

Where the device is used in the finding of the center or axes of plane figures, angular plates 8 are employed which are adjustably secured to the cross pieces 2 by the pins 4. Said plates 8 will be adjusted upon said cross pieces 2 in the same manner as the pins 4 as above described. When the plane figure to be acted upon is sufficiently small as 100 shown at 9 in Fig. 2, the plates 8 will be arranged as shown in full lines in said figure. After adjustment of said plate upon the cross pieces 2 the T-members of the device are adjusted relative to each other, in the 105 110

same manner as above described until the inner corners or points of the plates 8 register with the periphery of the figure, as shown in Fig. 2, the axes of the figure when 5 said parts are so adjusted being located at the contiguous edges of the stems 1. Where the plane figure as shown at 10 is too large to warrant the adjustment of the parts of the device to effect registration of the 10 inner corners of the plates 8 when positioned as mentioned, said plates 8 may be turned about as shown in dotted lines in Fig. 2, and said members adjusted to effect registration of the outer corners there- 15 of with the periphery of the figure, the result, as to the location of the axes, being the same in both cases. After the location of the axes has been determined, one of the members may be removed as before described and 20 the exposed longitudinal edge of the stem 1 of the remaining member utilized as a straight edge in the describing of the axis located.

A device of the construction set forth is 25 simple and economical in construction and hence may be manufactured at a low cost and will be found of high efficiency in use.

While I have illustrated and described the preferred form of construction for carrying 30 my invention into effect, this is capable of variation and modification without departing from the spirit of the invention. I, therefore, do not wish to be limited to the 35 precise details of construction set forth, but desire to avail myself of such variations and modifications as come within the scope of the appended claims.

Having described my invention what I 40 claim as new and desire to secure by Letters Patent is:

1. A device of the kind described comprising two substantially T-shaped members each consisting of a stem and a cross piece, said stems when said members are arranged 45 in operative relation being positioned with longitudinal edges contiguous; and means on said cross pieces equally distant from said contiguous edges and adapted for registration with the periphery of the object or 50 figure acted upon, substantially as described.

2. A device of the class described comprising two substantially T-shaped members each consisting of a stem and a cross piece, said stems, when said members are in opera- 55 tive relation, being positioned with longitudi- dinal edges contiguous and movable longitudinally relative to each other; and means

adjustably mounted on said cross pieces adapted when adjusted equally from said contiguous edges for registration with the 60 periphery of the object or figure acted upon, substantially as described.

3. A device of the class described comprising two substantially T-shaped members each consisting of a stem and a cross piece, 65 said stems, when said members are in operative relation, being positioned with longitudinal edges contiguous and movable longitudinally relative to each other; said cross pieces being provided with spaced perfora- 70 tions; and means coöperating with such of said perforations as are equally distant from said contiguous edges adapted for registration with the periphery of the object or figure acted upon, substantially as described. 75

4. A device of the class described comprising two substantially T-shaped members each consisting of a stem and a cross piece, said stems, when said members are in operative relation, being positioned with longitudinal edges contiguous and movable longitudinally relative to each other, said cross pieces being provided with perforations spaced equally in either direction from the 80 contiguous edges of said stems; means ad- justably mounted upon said cross pieces 85 adapted for registration with the periphery of the object or figure acted upon; and means engaging said perforations for releasably securing said registering means in 90 position, substantially as described.

5. A device of the class described comprising two substantially T-shaped members each consisting of a stem and a cross piece, 95 said stems, when said members are in operative relation, being positioned with longitudinal edges contiguous and movable longitudinally relative to each other, said cross pieces being provided with perforations spaced equally in either direction from the 100 contiguous edges of said stems; angular plates adjustably mounted upon said cross pieces adapted for registration with the 105 periphery of the object or figure acted upon; and means engaging said perforations for releasably securing said plates in position, substantially as described.

In testimony whereof I have signed my name to this specification in the presence of two subscribing witnesses.

CHARLES G. LUNDSTROM.
